Claims priority, application Switzerland Apr. 7, 1959
7 Claims. (Cl. 260—553)

The present invention relates to a process for the production of N_1 -arylsulfonyl- N_2 -alkyl ureas, whereby aryl signifies a phenyl radical, a lower alkylphenyl radical, a lower alkoxyphenyl radical, a halogenophenyl radical, or a p-aminophenyl radical, and alkyl is an alkyl radical containing from 2 to 8 carbon atoms.

N_1 -phenyl-, alkylphenyl-, -alkoxyphenyl- and -halogenophenyl-sulfonyl- N_2 -alkyl ureas have been known for some time (cf. British Patents Nos. 808,073, 808,072, and 808,071, Austrian Patent No. 196,413, and Swiss Patents Nos. 331,999 to 332,007).

It is also known from these patents to produce such N_1 -arylsulfonyl- N_2 -alkyl ureas by reacting N -arylsulfonyl ureas with alkyl-amines (cf. Swiss Patent No. 332,005). This process is called the transamination process by the chemist skilled in the art.

Repetition of the examples of Swiss Patent No. 332,005 applied to the production of N_1 -p-tosyl- N_2 -n-butyl urea gives when working without diluent a yield of 2.5%, and when working with o-dichlorobenzene as diluent, which is proposed in this specification, a yield of 5%.

Of course, such yields render impossible a technical application of this process. It was subsequently suggested to convert N_1 -aryl-sulfonyl- N_2 -acyl ureas into their salts by means of alkylamines and to heat the resulting salts to temperatures exceeding 100° C. (cf. Austrian Patent No. 195,436 and German Patent No. 1,043,318). Better yields can in fact be obtained with this process; it has, however, the disadvantage of requiring one step more than the simple transamination process.

N_1 -p-aminophenylsulfonyl- (abbreviated= N_1 -sulfanilyl-) N_2 -methyl-, - N_2 -ethyl-, - N_2 -propyl- and - N_2 -butyl ureas have been known for a long time (cf. Example 1 of East German specification No. 4,769, Example 11 of Danish specification No. 70,259, and Example 11 of Norwegian specification No. 71,236).

As a rule, compounds are used for the production of N_2 -substituted sulfanilyl ureas which contain in the para-position to the sulfonyl group a group which can be converted into a free amino group by hydrolysis or reduction. After completion of the formation of the sulfonyl urea grouping, this group is then converted into an amino group.

It has also been suggested to subject sulfanilyl urea to a so-called transamination using amines, adding acid in order to avoid side reactions (cf. page 1, lines 91—96 and Example 4 of East German specification No. 9,688). If this suggested process is used, i.e. if sulfanilyl urea hydrochloride is heated with butylamine hydrochloride in a mixture of dioxane and pyridine for a few hours, then a reaction mixture is obtained which is only partially soluble in dilute hydrochloric acid, so that not only does it contain the N_1 -sulfanilyl- N_2 -butyl urea formed but also many by-products. In Example 2 of East German specification No. 13,762 it is suggested to react sulfanilyl urea with butylamine in glacial acetic acid as solvent. The repetition of this example did not give the stated yield of 70% but only 52% of a product which was not pure. After purification of the product, the yield only amounted to 40% of the theoretical value.

It was now surprisingly found that N_1 -arylsulfonyl- N_2 -alkyl ureas can be obtained in a very simple manner and

2

in excellent yields and with very good purity when performing the reaction of an arylsulfonyl urea with an alkylamine in a ketone of a boiling point of approximately 90—120° C., preferably 100—120° C., at a molecular ratio of sulfonyl urea to alkylamine of 1:1.2, care being taken that the ammonia which is split off is removed from the reaction mixture as quickly and as completely as possible.

As already mentioned, aliphatic ketones boiling at temperatures of between 100 and 120° C. have proved to be advantageous solvents. The possibility that the reaction promoting influence of the aliphatic ketones is in any way connected with the intermediary formation of ketimines

(R: lower alkyl radicals; alkyl: an alkyl radical containing from 2 to 8 carbon atoms), cannot be excluded, but has not been proved.

It is advantageous to choose as solvent a ketone which is little or practically insoluble in water. After termination of the transamination, the resulting N_1 -arylsulfonyl- N_2 -alkyl urea can be brought into solution in the aqueous phase by the addition of an aqueous solution of an alkali hydroxide, while the ketone, which contains various impurities, is separated off. Thus, an additional purification of the end product is obtained.

As ketones complying with the above requirements shall be mentioned: methyl isobutyl ketone, methyl-n-propyl ketone, methyl secondary butyl ketone, diethyl ketone, ethyl isopropyl ketone, etc.

It is also possible to use a mixture of various ketones, such as for instance a higher and a lower boiling ketone, and to thus adjust the boiling point to the desired height.

The fastest possible removal of the split off ammonia can be accomplished in various manners known to the chemist skilled in the art. Since the reaction is carried through with the ketone at boiling point, it is necessary to provide the reaction kettle with a cooling device. The gas evolution can be facilitated by choosing a suitable cooling device. The wider the aperture of the cooling device is, the quicker does the ammonia escape.

The ammonia can also be removed at reduced pressure. Of great influence is the vigorous boiling of the ketone and the vigorous stirring of the solution. It is also possible to conduct through the reaction solution a strong flow of nitrogen or of another inert gas.

As arylsulfonyl ureas can be used: benzenesulfonyl urea, p-chlorobenzenesulfonyl urea, p-tosyl urea, p-methoxybenzenesulfonyl urea, p-chloro-m-methyl-benzene-sulfonyl urea, m,p-dimethyl-benzene-sulfonyl urea, p-aminobenzenesulfonyl urea, and other similarly substituted benzenesulfonyl ureas.

As alkylamines can be used: ethylamine, n-propylamine, isopropylamine, n-butylamine, isobutylamine, sec. butylamine, tert.butylamine, n-amylamine, isoamylamine, sec. amylamine, n-hexylamine, 2-hexylamine, heptylamine, and octylamine.

The advantage of the process for the production of N_1 -sulfanilyl- N_2 -alkyl ureas according to the present invention is obvious: it is known that sulfonyl ureas are sensitive to acids and bases. By the liberation of the amino group, which in practice takes place by the saponification of an acylamino group, the saponification action also attacks the sulfonyl urea grouping; the yield is thus reduced and, furthermore, the end product is contaminated.

Contrary to the processes formerly used the process according to the present invention permits to use the free p-aminophenylsulfonyl urea, and the resulting N_1 -sulfanilyl- N_2 -alkyl urea is obtained immediately in pure form.

The following examples are given for the purpose of illustrating the invention; they are not intended to limit the scope thereof.

Example 1.—N₁-Tosyl-N₂-n-Butyl Urea

214 g. of p-toluenesulfonyl urea are given into a mixture of 800 g. (=1000 cc.) of methyl isobutyl ketone and 80 g. (=100 cc.) of acetone, and then 80.3 g. of butylamine permitted to flow thereto within 15-30 minutes. A thick but still stirrable slurry results with a simultaneous rise in temperature of 15-20° C. The stirring is continued for 1/2-1 hour at a temperature of 20° C. The whole is then heated to boiling, whereupon evolution of NH₃ takes place. The evolution of NH₃ and thus the reaction are accelerated by heating as intensively as possible as well as by fractioning devices. After complete solution has been obtained, which occurs when the reaction is nearly completed and which depending on the kind of the reflux heating requires from 30 minutes to 2 hours, heating is continued for about 10-20 minutes, followed by quick cooling. The pale yellow reaction solution is stirred well with 1000 g. of an aqueous 4% sodium hydroxide solution, and the aqueous solution of the sodium salt of the N₁-p-tosyl-N₂-n-butylurea then separated off. The ketone layer is extracted twice with 50 cc. each of water. The combined aqueous solutions are adjusted to a pH value of 8.5-9 as quickly as possible while stirring by means of 120 g. of 10% H₂SO₄, and then filtered with 5 g. of Carboraffin-C. The carbon is washed with 150 cc. of water. The filtrate is then allowed to run within 1-2 hours while stirring into a mixture of 800 g. of methanol and 500 g. of 10% H₂SO₄. Seeding is necessary after the introduction of 1/10 of the total quantity. Cooling to 15-20° C. is followed by adjustment to a pH value of 3-3.5 and stirring for another 1/2-1 hour. The crystalline product is subsequently filtered off with suction or centrifuged and washed well with water. The white product, which can easily be filtered off by suction, is dried in an air drying oven at 40-60° C. The yield is: after 3/4 hour reflux heating 243 g. equally 90% of the theoretical value, with a melting point (corr.) of 127-128° C., and after 2 1/2 hours of reflux heating 230 g. equalling 85% of the theoretical value, with a melting point (corr.) of 126-127° C.

Example 2.—N₁-p-Chlorobenzenesulfonyl-N₂-n-Propyl Urea

164.3 g. of N-p-chlorobenzenesulfonyl urea are given while stirring into 800 cc. of methyl isobutyl ketone. Subsequently, 45.5 g. of n-propylamine are permitted to flow in, whereby a thick but still stirrable crystalline slurry results. The whole is now heated to boiling with continuous stirring, whereupon evolution of ammonia takes place lasting 35 minutes. The now clear solution is cooled to 20° C. and then stirred with 700 cc. of an aqueous 4% sodium hydroxide solution. The aqueous layer is separated off and the ketone layer extracted twice with 70 cc. each of water. The combined aqueous solutions are adjusted to a pH value of 8.7 by means of 10% sulfuric acid, stirred with 4 g. of Carboraffin-C, and the whole then filtered. The filtrate is given dropwise while stirring into a mixture of 700 cc. of methanol and 350 g. of 10% sulfuric acid. The final pH value is 3.2, and the dropwise introduction lasts approximately 3/4 hour. The whole is now stirred for another 15 minutes, and the crystalline slurry then filtered off with suction. After washing with water and drying in an air drying oven are obtained 165 g., corresponding to 85% of the theoretical value, of N₁-p-chlorobenzenesulfonyl-N₂-n-propyl urea of a melting point of 129° C.

Example 3.—N₁-p-Tosyl-N₂-Ethyl Urea

In a manner analogous to that described in the foregoing examples are obtained from 150 g. of N-p-tosyl urea, 35 g. of ethylamine (dissolved in 200 cc. of methyl isobutyl ketone) and 1200 cc. of methyl isobutylketone

as solvent after 3 hours of boiling and the usual working up 148 g. of N₁-p-tosyl-N₂-ethyl urea, equalling 87% of the theoretical value, which melts at 141-142° C.

Example 4.—N₁-p-Tosyl-N₂-n-Octyl Urea

When heating 150 g. of p-tosyl urea with 100 g. of n-octylamine in 700 cc. of methyl isobutyl ketone for 30 minutes to boiling and working up in a manner analogous to that of Example 1, 176 g. of N₁-p-tosyl-N₂-n-octylurea, corresponding to 77% of the theoretical value, which shows a melting point of 101-102° C., are obtained.

Example 5.—N₁-Sulfanilyl-N₂-n-Butyl Urea

215 g. of sulfanilyl urea are suspended in 960 g. (1200 cc.) of methyl isobutyl ketone and 87.7 g. (1.2 mol) of butylamine allowed to run in with stirring within the course of 15-30 minutes. A thick but stirrable slurry results, together with a rise in temperature of about 10° C. In order to complete the salt formation, stirring is continued for about a half hour and the reaction mixture then heated quickly to boiling point, whereupon evolution of ammonia takes place. The evolution of ammonia and thus the reaction are accelerated by boiling as intensively as possible as well as by fractioning devices. After complete solution has been obtained, which occurs when the reaction is almost completed, boiling is continued for about 10-15 minutes and the reaction mixture is then poured with intensive stirring into 1000 g. of aqueous 4% sodium hydroxide solution. The temperature thereby rises to about 40° C. After stirring well, the pale yellow sodium salt solution is separated off. The methyl isobutyl ketone layer is then extracted twice with 100 cc. each of water. The combined aqueous solutions are adjusted to a pH value of 8.5 with about 90 g. of 10% acetic acid, stirred with 10 g. of Carboraffin-C, filtered and washed with 700 cc. of water. The solution is diluted with a further 700 cc. of water, heated to 40-50° C., and the desired product is precipitated out, at first quite slowly with stirring and seeding, within about one hour with about 600 g. of 10% acetic acid to a pH of 6.0 to 6.5. After a few minutes, the 40-50° C. warm slurry, which consists of voluminous small crystalline needles, is filtered off with suction or centrifuged and washed well with water. Drying is carried out in an air drying oven at 40-60° C. The yield amounts to 244 g., i.e. 90% of the theoretical value.

Example 6.—N₁-Sulfanilyl-N₂-n-Butyl Urea

807 g. of sulfanilyl urea are suspended in 2000 cc. of methyl-n-propyl ketone, and a solution of 329 g. of n-butylamine in 2000 cc. of methyl-n-propyl ketone permitted to flow into this suspension. There results a thick but still stirrable slurry. The temperature rises automatically to 37° C. After adding a further 500 cc. of methyl-n-propyl ketone the whole is heated to boiling while stirring, which causes a strong evolution of ammonia. After 45-50 minutes the reaction is terminated and everything dissolved clearly. There follows cooling and then stirring with 3750 cc. of aqueous 1 N NaOH. The aqueous alkaline solution is separated off and the ketone layer extracted once more with 700 cc. of water. The combined aqueous solutions are adjusted to a pH value of 8.5, stirred with 40 g. of Carboraffin-C and then filtered. Acetic acid (2 N to 4 N dilutions are usable) in a fine jet is allowed to flow into the filtrate while stirring. This is followed by adjustment to a pH value of 6-6.5 and stirring for a further 15-30 minutes. The crystalline product is filtered off with suction, washed well with water and dried in an air drying oven. There result 925 g. of pure N₁-sulfanilyl-N₂-n-butyl urea. The yield corresponds to 91% of the theoretical value.

In the same manner can be reacted: p-tosyl urea with ethylamine, n-propyl amine, isopropylamine, aminolamine, isoamylamine, heptylamine, octylamine. It is also possible to use for the reaction p-methoxybenzenesulfonyl urea, p-

isopropylbenzenesulfonyl urea, p - fluorobenzenesulfonyl urea instead of p-tosyl urea.

What we claim is:

1. In an N_1 -arylsulfonyl- N_2 -alkyl urea forming reaction conducted in a solvent consisting essentially of an N -monocyclic-arylsulfonyl urea, wherein the aryl moiety is a member selected from the class consisting of phenyl, lower alkylphenyl, lower alkoxyphenyl, halogenophenyl and p-aminophenyl, and an alkylamine of from 2 to 8 carbon atoms, the improvement which comprises carrying out the reaction between said N -monocyclicarylsulfonyl urea and alkylamine in a ratio of 1:1.2 moles respectively in boiling ketone having a boiling point in the range of between 100° C. and 120° C., and removing the ammonia being split off as quickly as possible.

2. The method according to claim 1 wherein the ketone is substantially insoluble in water.

3. The method according to claim 1 wherein N -arylsulfonyl urea is p-toluenesulfonyl urea.

4. The method according to claim 1 wherein N -arylsulfonyl urea is N -p-chlorobenzenesulfonyl urea.

5. The method according to claim 1 wherein N -arylsulfonyl urea is sulfonylurea.

6. The method according to claim 1 wherein the ketone is methyl-n-propylketone.

7. The method according to claim 1 wherein the ketone is methylisobutylketone.
